STEAM BOILER FIREBOX

Clarence E. Hartley, Salisbury, N. C., assignor of
one-half to William T. Curlee, Salisbury, N. C.

Application June 9, 1942, Serial No. 446,391

2 Claims. (Cl. 122—68)

The present invention relates to new and useful improvements in fire boxes, particularly for steam locomotive boilers, and has for its primary object to provide, in a manner as hereinafter set forth, a device of this character comprising an overhead arch of a novel construction and arrangement for causing the draft to flow in such a manner as to substantially eliminate the cutting off of the heads of the crown bolts, the cutting out of the flues at the bottom inside of the sheet, excessive wearing of the crown sheet, et cetera, by cinders.

Another very important object of the invention is to provide an overhead arch of the aforementioned character for steam locomotive boiler fire boxes comprising a unique construction and arrangement of supporting tubes for the circulation of the boiler water.

Other objects of the invention are to provide an overhead arch for boiler fire boxes which will be comparatively simple in construction, strong, durable, highly efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in vertical longitudinal section through a locomotive fire box comprising an overhead arch constructed in accordance with the present invention.

Figure 2 is a cross-sectional view, taken substantially on the line 2—2 of Figure 1.

Figure 3 is a fragmentary view in side elevation of the boiler.

Figure 4 is a perspective view of the brick supporting and water circulating tubes.

Figure 5 is a detail view in side elevation of one of the washout plugs.

Referring now to the drawings in detail, it will be seen that reference numeral 1 designates generally a locomotive fire box comprising a crown sheet 2, side sheets 3, a fire door opening 4, et cetera. Mounted in the fire box 1 is the usual arch 5 comprising a plurality of circulating tubes 6 having mounted thereon fire bricks 7.

Mounted transversely in the upper portion of the fire box 1, at an intermediate point, is an overhead arch 8. In the embodiment shown, the arch 8 includes a tube 9 which extends between the side sheets 3 of the fire box 1. The tube 9 is of the longitudinal shape shown to advantage

in Figure 2 of the drawings. A longitudinal tube 10 has one end connected to the tube 9 at an intermediate point and its other end connected to the sheet 11 of the fire box 1.

5 The space between the tube 9 and the crown sheet 2 of the fire box 1 is closed by a series of fire bricks 12. The lower ends of the fire bricks 12 have formed therein transverse grooves or channels 13 for the reception of the tube 9. The two innermost bricks 12 are also formed or shaped on their lower ends to accommodate the adjacent end portion of the tube 10. Depending from the rear portions of the bricks 12 are integral shields or lips 14 which protect the tube 9 from forwardly flowing cinders.

10 It is thought that the manner in which the invention functions will be readily apparent from a consideration of the foregoing. Briefly, the construction and arrangement of the overhead arch 8 is such as to change the draft in a manner to prevent the cinders from striking, as at present, the crown sheet and the crown sheet bolt heads of the fire box 1. The cinders, after moving under the arch 8, move forwardly and when they enter the boiler flues they are traveling in a direction substantially in alignment with said flues thereby preventing the cutting out of the flues in the boiler ahead of the sheet 15. The water in the boiler circulates freely through the tubes 9 and 10 in a manner to materially promote efficiency. Removable washout plugs 16 are threadedly mounted in the boiler 17 in alignment with the ends of the tube 9. As hereinbefore stated, the lips or shields 14 protect the tube 9 against damage from cinders.

15 It is believed that the many advantages of an overhead arch constructed in accordance with the present invention will be readily understood, and although a preferred embodiment of said arch is as illustrated and described, it is to be understood that changes in the details of construction and in the combination and arrangement of parts may be resorted which will fall within the scope of the invention as claimed.

40 What is claimed is:

1. The combination with a locomotive fire box including a crown, side and a back sheet, respectively, and an arch above the bottom of said box including longitudinally extending tubes and a wall thereon forming a rear opening in the arch, of an auxiliary draft deflecting transverse arch in said box above the arch first mentioned and spaced forwardly of said opening, said auxiliary arch comprising a water circulating tube extending 45 between the side sheets and anchored therein,

a refractory brick wall supported by said tube and closing the space between the tube and the crown sheet, and a longitudinal water circulating tube extending between the first mentioned tube and the rear sheet of the fire box in the center of said box.

2. The combination with a locomotive fire box including a crown, side and a back sheet, respectively, and an arch above the bottom of said box including longitudinally extending tubes and a wall thereon forming a rear opening in the arch, of an auxiliary draft deflecting transverse arch in said box above the arch first mentioned and

spaced forwardly of said opening, said auxiliary arch comprising a water circulating tube extending between the side sheets and anchored therein, a refractory brick wall supported by said tube and closing the space between the tube and the crown sheet, and a longitudinal water circulating tube extending between the first mentioned tube and the rear sheet of the fire box in the center of said box, said bricks having depending lips covering the side of the first mentioned tube nearest said opening to protect said tube.

CLARENCE E. HARTLEY.
